UNITED STATES PATENT OFFICE

2,007,757

THERMAL CUT-OUT

Arthur R. Hand, Ballston Lake, N. Y., assignor to
General Electric Company, a corporation of
New York

Application August 24, 1931, Serial No. 558,903
Renewed January 22, 1935

7 Claims. (Cl. 200—117)

My invention relates to fusible cutouts or fuses and more specifically to tension fuses of low current rating for high voltage circuits.

Tension fuses have been used for high voltage circuits with a spring directly connected to the fusible element to separate the severed ends upon the blowing of the fuse. While this method of connecting the fusible element directly to the tension device is satisfactory when the fusible element is large, considerable difficulty is encountered when the rating of the fuse requires a fusible element which is small in that it does not have sufficient tensile strength to withstand the spring tension.

The object of my invention is to provide a tension fuse for high voltage circuits in which a fusible element connected to the spring may be made any size to withstand the spring tension regardless of the current rating of the fuse with auxiliary means to cause the severing of the fusible element at the rated current of the fuse.

What I consider to be novel and my invention will be better understood by reference to the following specification and appended claims.

In the accompanying drawing, Fig. 1 is a cross sectional view of a fusible cut-out embodying my invention, and Fig. 2 is an enlarged cross sectional view of the ends of the fuse at right angles to the view in Fig. 1.

In accordance with my invention, the main fusible element is made large enough to withstand the requisite tension and an auxiliary pilot filament is connected in series with the main fusible element but relieved of all tension so that it will be melted by the overload on the circuit and will cause a subsequent rupture of the main fusible element.

The cut-out comprises a shell 10 of insulating material which is substantially filled with an incombustible material or filler 11 which may be a mixture of calcium sulphate and calcium carbonate, or other suitable material. A fluid may be used as a substitute for the granular filler shown in the drawing. To retain the filler 11 within the shell 10, metallic cups 12 and 13 are placed in each end of the shell and project within it a short distance. End cups 12 and 13 are provided with circular openings 14 and 15 respectively to permit the escape of gases generated by the blowing of the fuse.

A fusible element 16 is anchored by a bar of insulating material 17 which is seated in slots in the projecting end of cup 12 and extends through an opening in the center of the cup, 55 through the filler 11, and opening at one side of

cup 13, and is connected to a spring driven drum 18 journaled in slots in cup 13. As best indicated in Fig. 2, the central opening in the end cup 12 through which the fusible element 16 passes is larger than necessary to permit the passage of the fusible element and serves as an arcing edge, as will be explained later. An auxiliary fusible element or pilot filament 19 is connected to the fusible element 16 adjacent its point of anchorage and is connected to the end cup 12 near the central opening.

Contact caps 20 and 21 are provided for enclosing the ends of the shell and to make electrical connection with the circuit which the fuse is used to protect. These contact caps are secured in position and electrically connected with the end cups 12 and 13 by means of screws threaded into apertures in the end cups. Circular openings or vents are provided in the contact caps to permit the escape of gases generated upon the blowing of the fuse.

In order to guide the fusible element through the enlarged central opening in end cup 12, and at the same time prevent the escape of the filler through the enlarged opening, a plate 22 of insulating material having a small central opening somewhat larger than fusible element 16 to permit its easy passage is pressed within a central cavity of the cup. Crinoline discs 23 may also be placed between the filler and end cups in order to prevent the loss of the filler through the vents 14 and 15 provided in the end cups.

Spring driven drum 18 is mounted on a shaft 24 and adapted to rotate freely thereon. Shaft 24 is secured rigidly in slots in the projecting end of cup 13 and may be secured in position against rotation by soldering or welding it to the end cup. Drum 18 is driven by a spiral spring 25 which is connected at its inner end to shaft 24 and at its outer end to the outer periphery of the drum 18.

The space between the end cup 12 and contact cap 20 where the pilot filament and fusible element are blown is generally termed the explosion chamber. In order to prevent an arc within this chamber being drawn between the fusible element and the contact cap 20 a sleeve 26 of insulating material and a cooperating disc 27 also of insulating material are placed within the contact cap. Insulating disc 27 has openings cooperating with the openings in the contact cap to permit the escape of gases.

It may be desirable to waterproof the shell 10 to prevent moisture or water impregnating the shell which would tend to make the shell 55

conducting and complete a path for current along the surface of the shell between the end caps.

The electrical circuit through the fuse extends from the contact cap 20 through the end cup 12, pilot filament 19, fusible element 16, spring wound drum 18, spring 25, shaft 24, end cup 13 to contact cap 21. When the current flowing through the fuse is in excess of the rating of the fuse the pilot filament 19 is melted. This interrupts the metallic circuit through the fuse between the end cup 12 and the fusible element 16. As the pilot filament 19 melts, gases are generated and an arc is set up. This causes the drawing of an arc between the end cup 12 and the fusible element 16. Since the shortest distance between the end cup 12 and the fusible element 16 is at the point of passage of the fusible element through the central opening or arcing edge of the end cup, the arc will be concentrated between this arcing edge and the adjacent portion of the fusible element and will cause a rapid melting of the fusible element due to the intense heat at the point the arc strikes the fusible element. When the fusible element 16 is ruptured, spring driven drum 18 will be released and will rapidly coil the fusible element around it as it rotates and thus will draw out the arc from the end cup 12 through the filler 11. The filler 11 will serve to cool the rapidly elongating arc and quickly quench it. The protected circuit will thus be interrupted quickly without the generation of a large amount of heat and possible damage to adjacent apparatus.

From the foregoing it may be seen that by the arrangement of a main fusible element of sufficient tensile strength to withstand the spring tension, and an auxiliary fusible element or pilot filament not subjected to any spring tension which may be made small enough to be blown by any desired overload and will cause a subsequent blowing of the main fusible element, a fuse is provided that may be used to protect a high voltage circuit regardless of how small the current rating of the fused circuit may be and which is reliable and quick acting.

What I claim as new and desire to secure by Letters Patent of the United States, is:

1. An electric cut-out comprising a shell of insulating material, a fusible element extending within said shell, a spring driven drum connected to one end of the fusible element, a pilot filament, and means for severing the fusible element upon the blowing of the pilot filament.

2. An electric cut-out comprising a shell of insulating material, a fusible element extending within said shell, a chamber containing a filler of incombustible material, a spring driven drum connected to one end of the fusible element and adapted to withdraw it through said chamber upon the rupture of the opposite end, a pilot filament, and means for severing the fusible element upon the blowing of the pilot filament.

3. An electric cut-out comprising a shell of insulating material, an incombustible material substantially filling said shell, an explosion chamber in one end of the shell, a spring mounted in the other end of the shell, a fusible element extending from said explosion chamber through the incombustible material and connected to the spring, a metallic cup located in the explosion chamber and having an enlarged central opening through which the fusible element passes, and a pilot filament connected between the fusible element and the metallic cup, whereby an arc is drawn between the metallic cup and the fusible element upon the blowing of the pilot filament to sever the fusible element. 10 15

4. An electric cut-out comprising a shell of insulating material, an incombustible material substantially filling said shell, an explosion chamber in one end of the shell, a spring driven drum mounted in the opposite end of the shell, a fusible element extending from the explosion chamber through the incombustible material and connected to the spring driven drum, a metallic cup located in the explosion chamber and having an enlarged central opening through which the fusible element passes, and a pilot filament connected between the fusible element and the metallic cup, whereby an arc is drawn between the central opening of the metallic cup and the fusible element upon the blowing of the pilot filament 20 25 30

5. An electric cut-out comprising a shell of insulating material, an incombustible material substantially filling said shell, an explosion chamber in one end of the shell, a spring driven drum mounted in the other end of the shell, a fusible element anchored in the explosion chamber extending through the incombustible material and connected to the spring driven drum, a metallic cup located in the explosion chamber and having an arcing edge through which the fusible element passes, and a pilot filament connected between the fusible element and the metallic cup, whereby an arc is drawn between the arcing edge of the metallic cup and the fusible element upon the blowing of the pilot filament to sever the fusible element. 35 40 45

6. An electric cut-out comprising a shell, a fusible element extending within said shell, means placing the fusible element under tension, a pilot filament connected at one end to the fusible element, and means to cause an arc to strike to the fusible element upon the blowing of the pilot filament. 50

7. An electric cut-out comprising a shell, a fusible element extending within said shell, means placing the fusible element under tension, a pilot filament connected at one end to the fusible element and adapted to melt before the fusible element, and means to cause an arc to strike to the fusible element and sever the fusible element upon the blowing of the pilot filament. 55 60

ARTHUR R. HAND.
